TABLE LAMP OR SIMILAR ARTICLE

Harry B. Gross, Forest Hills, N. Y., assignor to Joseph Wolsky, Brooklyn, N. Y.

Application February 23, 1955, Serial No. 34,627

Term of patent 7 years

(Cl. D48—20)

FIG. 1

To all whom it may concern:

Be it known that I, Harry B. Gross, a citizen of the United States of America, residing at Forest Hills, county of Queens, State of New York, have invented a new, original, and ornamental Design for a Table Lamp or Similar Article, of which the following is a specification, reference being had to the accompanying drawing, forming part hereof.

Fig. 1 is a front elevational view of a table lamp showing my new design;

Fig. 2 is a side elevational view thereof; and

Fig. 3 is a top plan view thereof as seen from the top of Fig. 1, with the lamp shade removed.

I claim:

The ornamental design for a table lamp or similar article, substantially as shown.
